DESCRIPTION

U.S. PATENT DOCUMENTS

FIG. 1 shows a top perspective view of a notched mission tile according to the present invention.

479,442 A	7/1892	Marwick
522,879 A *	7/1894	Cohen, S.K. 52/519
2,510,416 A	6/1950	Pretty
2,624,298 A	1/1953	Farren
3,309,831 A	3/1967	Misch, A. et al.
3,440,777 A	4/1969	Martin et al.
D218,540 S *	8/1970	Powell D25/140

FIG. 2 shows a bottom perspective view of the notched mission tile of FIG. 1.

(Continued)

FIG. 3 shows a left side view of the notched mission tile of FIG. 1.

FOREIGN PATENT DOCUMENTS

FIG. 4 shows a front view of the notched mission tile of FIG. 1.

DE	93888	11/1972
EP	0095420	11/1983
EP	0175500	3/1986
FR	1259641	3/1961
GB	416649	9/1934
GB	2046808	11/1980

FIG. 5 shows a right side view of the notched mission tile of FIG. 1.

FIG. 6 shows a rear view of the notched mission tile of FIG. 1.

FIG. 7 shows a top view of the notched mission tile of FIG. 1; and,

FIG. 8 shows a bottom view of the notched mission tile of FIG. 1.

Portions or features of the notched mission tile shown in broken lines in the drawings form no part of the claimed design. Portions or features of the notched mission tile absent in the drawings form no part of the claimed design.
